UNITED STATES PATENT OFFICE.

CHRISTIAN F. KLEIN, OF BALTIMORE, MARYLAND.

DESIGN FOR A MATCH-HOLDER.

41,969.

Specification for Design.

Patented Dec. 12, 1911.

Application filed September 9, 1911. Serial No. 648,543. Term of patent 3½ years.

To all whom it may concern:

Be it known that I, CHRISTIAN F. KLEIN, a citizen of the United States, residing at Baltimore, in the State of Maryland, have invented a new, original, and ornamental Design for a Match-Holder, of which the following is a specification, reference being had to the accompanying drawing, forming part thereof.

The figure is a perspective view of the match holder, showing my new design.

I claim—

The ornamental design for a match holder, as shown.

In testimony whereof I affix my signature in presence of two witnesses.

CHRISTIAN F. KLEIN.
